UNITED STATES PATENT OFFICE.

RANSOM Y. BOVEE, OF BLOOMINGTON, ILLINOIS.

WRENCH.

1,201,015.

Specification of Letters Patent. Patented Oct. 10, 1916.

Application filed May 28, 1915. Serial No. 30,958.

To all whom it may concern:

Be it known that I, RANSOM Y. BOVEE, a citizen of the United States, residing at Bloomington, in the county of McLean and State of Illinois, have invented a certain new and useful Improvement in Wrenches, of which the following is a specification.

My invention relates to improvements in monkey wrenches, and has for one object 10 to provide a new and improved form of monkey wrench in which the sliding head is held in position on the shank by a ratchet or tooth arrangement, but it may still snugly grip every individual size of nut no matter 15 what its dimensions.

Another object is to provide a monkey wrench which furnishes its own ratchet action.

Another object is to provide a monkey wrench which will grip a nut firmly and rigidly and prevent slipping of the nut.

Other objects of my invention will appear in the specification.

The invention is illustrated in the accompanying drawings, wherein—

Figure 1 is a side elevation of the wrench; Fig. 2 a plan view; Fig. 3 a side elevation in different position.

Like parts are indicated by like letters 30 throughout the several figures.

A is the shank of the wrench. At one end it has rigidly attached thereto a jaw member A¹. At the other end it enters into and is pivoted in position in the hollow handle A² 35 being held upon the pivot A³. This hollow handle as indicated is enlarged about this pivotal point to form a rigid powerful support for the pivoted end of the shank. The end of the shank is notched as at A⁴, so that 40 it may be engaged by a pin A⁵. This pin slides within the handle A², being guided by a track A⁶. It has a knurled thumb-piece A⁷ projecting outward through a slot A⁸ in the handle A², and is held in whatever position 45 it is put by the spring A⁹, so that when in the position shown in Fig. 1 it engages the shank and prevents relative rotation of shank and handle, whereas, in the position shown in Fig. 3, being withdrawn, it dis- 50 engages the shank and permits rotation.

B is a sliding carriage free to slide along the shank A. It carries the sliding jaw B¹ in opposition to the fixed jaw A¹.

B² is a lever arm pivoted on the carriage 55 B, having a serrated or toothed face B³, in opposition to the toothed ratchet bar B⁴.

B⁵ is a spring engaging the thumb-piece B⁶ and adapted to thrust the surface B³ yieldingly but firmly against the bar B⁴. The bar B⁴ is pivoted at B⁶ in the handle A², 60 and has an extension or pin B⁷ slidable in a bracket B⁸ on the end of the shank A.

B⁹ is a coil spring surrounding this pin and adapted to be compressed as indicated between the bracket or lug B⁸ and the shoulder B¹⁰ adjacent the pivotal point B⁶.

The handle A² is provided with an extension lip or shroud C which has a two-fold function. It prevents the hands of the operator from contact with the end of the extension pin B⁷, and it guides and protects that pin and prevents displacement of the parts. Under some circumstances the end of the pin can come in contact with the inside of this shroud to assist in locking the parts together for resisting too free disengagement of the parts when this is undesirable. The rotation of the handle and the shank with respect one to the other as shown in Fig. 3, 70 is limited by the compression of the spring 75 between the collar and the lug. The rotation in the other direction is limited as shown in Fig. 1 by the engagement of the back side of the shank behind the pivotal point with the wall of the handle A².

It will be noted that, in order to permit relative movement of the handle without disturbing the parallelism of the ratchet bar and shank, the pivotal connection between the handle and the ratchet bar is slidable as 80 indicated, the pivoted pins sliding in a slot on the ratchet bar.

It will be evident that while I have shown in my drawings an operative device, still many changes might be made both in size, 95 shape and arrangement of parts without departing from the spirit of my invention, and I wish, therefore, that my drawings be regarded as in a sense diagrammatic.

The stop A⁵ may be moved back a short 100 distance without moving it out of the path A⁴. When this is done, it is, of course, out of engagement with the part A⁴ when the parts are in the position shown in Fig. 1, thus the shank is free to move through a 105 small angle with respect to the handle before it is stopped or limited by the stop member A⁵ and thus it is possible to compensate for inaccuracy in position of the jaw B¹ with respect to the toothed bar B⁴. When 110 the movement from one tooth to the next does not give the proper adjustment moving

the part A⁵ back and forth will cause slight controllable movement with respect to the shaft.

The use and operation of my invention are as follows:—When the parts are in the position shown in Fig. 1 with the handle and shank locked against relative movement, the operator manipulates the wrench in the well known manner, presses down on the 10 thumb-piece, frees the teeth in engagement and slides the carriage and sliding jaw back and forth along the shank, releasing the thumb-piece when the jaws are at the proper distance from one another. This gives him a 15 rigid wrench of the well known type. However, because the teeth on the ratchet bar and the lever must be of a certain minimum size in order to prevent breakage or stripping, it is evident that it is impossible always to have the proper distance between the two jaws to exactly fit the nut to be turned. The operator obviates this difficulty by releasing or moving back the latch pin, thus permitting a free rotary movement of 20 25 the handle and shank with respect one to another, resisted only by the compression of the coil spring. In this case he would slightly reduce the distance between the two jaws, the wrench in the position shown 30 in Fig. 1, and would engage the nut by bending back the handle. This will draw the sliding jaw along the shank as shown in Fig. 3, and permit the operator to grip the nut snugly and firmly. The tension of 35 the spring will of course tend to cause the handle and shank to assume their normal positions, and thus the nut will be firmly gripped by the spring tension, even before the operator brings any pressure to bear 40 upon the handle. When he does this pulling toward him in the usual way, the two jaws will, of course, come powerfully together and grip the nut firmly. If now the operator wishes to operate the wrench as a 45 ratchet wrench, he presses back on the handle and the pressure being reversed, the handle will assume the extreme position shown in Fig. 3, the jaw will be withdrawn far enough to permit the wrench to turn 50 about the nut without gripping the nut until the next face has been reached. The operator then exerts a pull and moves the nut around in the forward direction in the usual manner.

55 The pressure of the spring B⁹, of course, normally holds the toothed bar B⁴ in a forward position keeping the end of the part B⁷ yieldingly out of engagement with the resistance plate C. When the wrench is 60 closed upon the object to be gripped the tension on the handle will cause it to rock slightly with respect to the shank to overcome the spring resistance and thrust the end B¹¹ into engagement with the curved resistance plate C thus frictionally resisting

any movement of the handle with respect to the shank. The spring B⁹ is thus compressed between a part on the shank and a part on the toothed bar. The function of the pivot pins B⁶ when the handle is moved in the reverse direction is, of course, merely to draw the toothed bar B⁴ back and carry with it the slideable jaw to disengage the nut. The plate C, it will be observed, has a cam surface, the upper edge of which is 75 nearer to the pivot A³ so that when the operator grips the nut with the handle A² bent back and commences to turn it by rotating the handle A² forward the handle tends to rotate about the pivot A³. The cam surface forcing the member B forwardly firmly clamps the jaws B¹, A¹ upon the object to be turned thus preventing any release of the object and since this cam surface applies frictional resistance against the 80 part B¹¹, the wrench can be used sidewise or forward or any angular arrangement except backward.

I claim:

1. A wrench comprising a handle, a shank pivotally mounted thereon, a jaw slideable along the shank, a ratchet bar parallel with the shank and adjustable in engagement with the jaw and in loose pivotal engagement with the handle, a spring interposed between the shank and the bar to normally thrust the jaw away from the handle. 90 95

2. A wrench comprising a handle, a shank pivoted thereon, a lug carried by the shank, a jaw slideable on the shank, a ratchet bar 100 slideable along the shank, an adjustable connection between it and the jaw, said bar being slideable through the lug on the shank and loosely pivoted on the handle, a spring interposed between the bar and the lug to 105 yieldingly thrust the bar and jaw away from the end of the shank, a cam carried by the handle in opposition to the end of the bar.

3. A wrench comprising a handle, a shank pivotally mounted thereon, a jaw slideable along the shank, a ratchet bar parallel with the shank and adjustable in engagement with the jaw and in loose pivotal engagement with the handle, a spring interposed between the shank and the bar to normally thrust the jaw away from the handle, a cam carried by the handle in engagement with the end of the ratchet bar, to thrust the 110 115 ratchet bar out from the handle in response to rotation of the handle with respect to the shank.

4. A wrench comprising a handle, a shank pivoted thereon, a lug carried by the shank, a jaw slideable on the shank, a ratchet bar 120 125 slideable along the shank, an adjustable connection between it and the jaw, said bar being slideable through the lug on the shank and loosely pivoted on the handle.

5. A wrench comprising a handle, a shank 130

- pivoted thereon, a lug carried by the shank, a jaw slidable on the shank, a ratchet bar slidable along the shank, an adjustable connection between it and the jaw, said bar being slidable through the lug on the shank and loosely pivoted on the handle, a spring interposed between the bar and the lug to yieldingly thrust the bar and jaw away from the end of the shank.
6. A wrench comprising a handle, a shank pivoted thereon, a jaw slidable on the shank, a thrust member held in parallelism with the shank and connected to the jaw, yielding means for normally holding the handle in substantial parallelism with the shank, said means comprising a spring interposed between the shank and the handle and mounted on the thrust member, and a cam member on the handle in opposition to the end of the thrust member to positively force the jaw along the shank away from the handle. 20
25
- 10 6. A wrench comprising a handle, a shank pivoted thereon, a jaw slidable on the shank, a thrust member held in parallelism with the shank and connected to the jaw, yielding means for normally holding the handle in substantial parallelism with the shank, said means comprising a spring interposed between the shank and the handle and mounted on the thrust member, and a cam member on the handle in opposition to the end of the thrust member to positively force the jaw along the shank away from the handle. 30
- 15 7. A wrench comprising a handle, a shank

pivoted thereon, a jaw slidable on the shank, a thrust member held in parallelism with the shank and connected to the jaw, yielding means for normally holding the handle in substantial parallelism with the shank, said means comprising a spring interposed between the shank and the handle and mounted on the thrust member, and a cam member on the handle in opposition to the end of the thrust member to positively force the jaw along the shank away from the handle.

In testimony whereof, I affix my signature in the presence of two witnesses this 24 day of May 1915.

RANSOM Y. BOVEE.
